[57] CLAIM

The ornamental design for a shirt, as shown and described.

DESCRIPTION

FIG. 1 is a front perspective view of a shirt showing my new design.

FIG. 2 is a rear perspective view;

FIG. 3 is a sectional view taken along line 3—3 in FIG. 1;

FIG. 4 is a sectional view taken along line 4—4 in FIG. 1;

FIG. 5 is a sectional view taken along line 5—5 in FIG. 2; and

FIG. 6 is a sectional view taken along line 6—6 in FIG. 2.

The sleeve and center back ornamentation is fabric which contrasts with that of the rest of the shirt.
